UNITED STATES PATENT OFFICE.

ELOF NORDSTROM, OF NEWARK, NEW JERSEY, ASSIGNOR TO AMERICAN DAN STOPPER COMPANY, OF BRIDGEPORT, CONNECTICUT, A CORPORATION OF CONNECTICUT.

CAP MAKING AND PACKAGING MACHINE.

Specification of Letters Patent. Patented Oct. 29, 1918.

1,283,273.

Application filed February 9, 1916. Serial No. 77,192.

To all whom it may concern:

Be it known that I, ELOF NORDSTROM, a citizen of the United States, residing at Newark, in the county of Essex and State of New Jersey, have invented certain new and useful Improvements in Cap Making and Packaging Machines, of which the following is a full and clear specification.

This invention relates to a machine which successively and continuously makes bottle caps and charges them into holders for shipment to any point at which they may be used. One of the objects of the present invention is to provide an improved packaging device for shipping caps from a point where they are manufactured to a point where they are to be used, said device being adapted to be charged automatically on a machine for that purpose and to feed caps automatically to a machine which applies them to bottles. Another object is to provide improved means for charging these packaging devices and furthermore contemplates in connection therewith means for automatically constructing the caps and delivering them therefrom to the charging means. Another object is to provide an improved machine embodying cap-shaping dies which move in succession from cap forming position into positions for discharging the caps into the holders. Other and further objects will appear in the specification and be pointed out in the appended claims, reference being had to the accompanying drawings in which:

Figure 1 is a side elevation of the preferred embodiment of my invention, parts being broken away and parts shown in section;

Fig. 2 is an end elevation of the same, parts being broken away;

Fig. 3 is a top plan view of the same, the cork insert holding hopper being removed;

Fig. 4 is a fragmentary plan view on an enlarged scale, parts being broken away;

Fig. 5 is a fragmentary section on the line V—V, Fig. 4, a fragmentary portion of the rotary table being shown in side elevation but broken away and shown in section adjacent the cap-holder;

Fig. 6 is a fragmentary section across the long diagonal of one of the tubular holders, the plunger being shown in elevation;

Figs. 7 to 12 inclusive are diagrams illustrating the successive operations of the machine;

Fig. 13 is a part vertical section and part side elevation of the tape feeding and blank cutting mechanism;

Fig. 14 is a sectional view of the insert-charging mechanism, parts being shown in elevation.

In the preferred embodiment of my invention shown on the drawings, the posts 1, serve to mount a bed plate 2, said bed plate being provided with lateral flanges 3, and 65 with corner pads 4, which surmount the corner posts 1. At one end of the bed plate 2, a frame or bracket 5 projects upwardly and has a 90° bend therein to provide forwardly extending portions 6 as shown in Fig. 3. Said portions 6 unite in a laterally projecting plate or portion 7 which is joined to the upper end of a side bracket or standard 8 which is secured at its lower end to one of the side flanges 3 of the bed plate 2. As 75 shown in Fig. 2, a pair of spaced lugs 9 depend from the bed plate 2 and are suitably arranged to have the base flange 10 of a bracket 11 secured thereto. Said bracket together with another similar one (not 80 shown) at the other rear end of the machine serves to journal a shaft 12 which extends longitudinally of the machine. Said shaft has keyed thereto a beveled gear 13 which meshes with a beveled pinion 14, said pinion being keyed to a power shaft 15 which carries a belt driven wheel 16. Keyed to the rear end of the shaft 12 is an eccentric 85 17 which carries a strap 18 connected by a rod 19 with a lever 20, said lever, as shown 90 in Fig. 3, being keyed to a vertical shaft 21 in Fig. 3, being keyed to a vertical shaft 21 journalized in suitable bearings carried by rigid portions of the main frame of the machine. An arm 22 (see Fig. 3) is pivotally 95 connected at 23 with one end of a connecting rod 24, the other end of said rod being pivotally connected at 25 with an arm 26 of a bell-crank lever, the other arm 27 of which is connected to a reciprocatory rod 28 which drives a device hereinafter referred 100 to for feeding a metal tape 29 indicated in dot and dash lines on Fig. 1, a supply of such tape being preferably in the form of a roll 30 carried by a spindle 31 journaled in the bracket 5. As the tape 29 is fed forwardly, suitable means are operated to cut blanks therefrom for forming the metallic portions of the caps. Keyed to the shaft 105 12 as shown in Fig. 1 is a cam block 32 having cam grooves 33 and 34 provided in its 110

peripheral wall. Journalled on a pin 35 is a bell-crank lever 36, the downwardly extending arm thereof being provided with a cam roller running in the cam groove 33 while the forwardly extending arm thereof is pivotally connected to a vertical rod 37. Another bell crank lever 38 is journalled on a pin 39 and has its lower arm provided with a cam roller running in the cam groove 5

10 34. The forwardly extending arm of this bell crank is connected at 39' to a vertical rod 40 disposed immediately behind the rod 37 according to Fig. 1. The upper ends of the rods 37 and 40 are connected respectively 15 to lever arms 41 and 42, the former being rigid with an elongated hub journalled on a pin 43 and carrying forwardly extending arms 44 which interengage with a spool 45 on the upper end of the blank cutting plunger 142 similar to that shown and described in my co-pending application, Ser. No. 48,210, filed August 31, 1915. Also similar 20 to that shown in the above mentioned application is the cap shaping device which includes the plunger 46 provided with a spool 47 which interengages the forwardly extending arms 48 which are oscillated about the pin 49 by the movement of the lever arm 42.

25 30 The spool 45 carries a plate 144 which reciprocates a knife 145 cutting off the unused remnant of the ribbon or tape 130 after each operation. Said ribbon or tape is fed forwardly by reciprocable gripper blades 131 which are pivotally connected at 132 to a bell crank lever 133 pivotally mounted by a pin 134 in reciprocable slides 135 which are yieldably held by interposed springs 136 within the guideways 137 as explained in 35 my above identified application. A reciprocating rod 28 pivoted to a member 139 transmits an oscillatory movement to a pin 140 to rock the bell crank lever 133 immediately before each endwise movement of the grippers 131. The ribbon or tape feeds through a slotted block 141, the blanks being stamped therefrom by plunger 142. Plunger 46 which is provided with an enlarged lower end 147, next moves downwardly to shape 40 the blank in the die 150.

45 A connecting rod 50 having its lower end connected at 51 to the forwardly presented arm of the bell-crank 38, is connected at 52 with a lever 53 which oscillates about the axis of a hub 54. Said lever 53 is provided with a forward arm 55 and a depending arm 56 which is connected to the upwardly presented arm 57 of a lever pivoted at 58 and also provided with a forwardly presented 50 arm 59. The arms 55 and 59 respectively operate oppositely arranged slides which carry suitable dies for stamping legends and corrugations on the metal caps in a manner substantially similar to that pointed out in 55 my above referred to application. A hopper

60 for cork inserts is provided with suitable mechanism (not shown) which feeds said inserts to a tube 61 (see Figs. 1 and 14), said tube being adapted to convey the inserts to a reciprocating slide 62 which is operated by a connecting rod 63 which is in turn driven by a crank arm 64, the crank arm 64 being keyed to the vertical shaft 21 and therefore operated by the eccentric 17 through its strap 18. The slide 62 places the cork inserts 151 one by one into the path of a reciprocating plunger 153 which forces the inserts down into the caps within the successive dies carried by the rotary table 71. Said plunger 153 is driven by a crank arm 155 keyed to the shaft 49 which is oscillated by the lever arm 42 operated by cam lever 38 (see Figs. 1 and 3). A crank arm 65 which is also keyed to the shaft 21 is connected at 66 with a connecting rod 67, said rod 67 being connected at 68 by a housing 69 which oscillates about the axis 70 of the rotary table 71. A pawl 72 which is pivotally mounted at 73 within said housing 69 is adapted to engage a ratchet 74 which is rigidly secured to the rotary table 71. The teeth of said ratchet are suitably spaced to coöperate with the pawl 72 in rotating the table 71 a distance equal to the space between two adjacent cap shaping dies carried by said table, at each stroke of the rod 67. Cap shaping dies 75 are arranged on the table 71 and adapted to convey caps from the position in which they are formed into suitable positions to be inserted into cap holders or shipping tubes to be presently described. Referring more particularly to Figs. 4, 5, and 6, it will be observed that the forward end of the bed plate 2 serves to mount an arcuate standard or bracket 76 provided with an overhanging arcuate flange 77 in which are formed a plurality of openings or sockets 78 for the reception of suitable cap holding tubes 102, 103, 104, 105, and 106. As shown best in Fig. 5, each socket 78 is provided with suitable springs or supports 80 secured to the upper surfaces of the flange 77 and depending into the holes or sockets 78. Said springs or supports are provided with hooks or projections 81 for carrying said tubes 102, 103, 104, 105, 106 at a suitable distance above the rotary table 71 which rotates in the recess 82 formed in the bracket 76. As shown best in Figs. 4 and 5, a plurality of bifurcated studs 83 are threaded into the bed plate 2 and serve to pivotally mount a plurality of cam levers 84, 85, 86, 87, and 88. As shown best in Fig. 5 each of these cam levers carries suitable cam rolls 89 which are successively engaged by cam arms 90, 91, 92, 93, and 94, which are keyed to a cam shaft 95. Cam shaft 95 carries a large beveled gear 96 which meshes with a beveled pinion 97 on the forward end of the longi- 130

tudinal shaft 12. Each of the cam levers 84, to 88 inclusive are provided at their free ends with rounded protuberances 98 which are adapted to engage the flanges 99 on the lower ends of the plungers 100, said plungers being reciprocably mounted in spaced annular flanges 101 carried by the bracket or standard 76. It will be understood from this description that as the formed caps are placed into the tubes 102 to 106, said caps are displaced upwardly from the cap shaping dies into said tubes, the springs 81 serving to permit the movement of said caps into the tubes but preventing them from following the plunger downwardly at its return stroke. Preferably this operation is carried out in the order indicated diagrammatically in Figs. 7 to 12 inclusive. Thus in Fig. 7, the table 71 is shown to carry caps 107, 108, 109, 110, 111, 112, 113, 114, and 115. This figure furthermore shows cap 107 has reached a position in register with the cap holding tube 104. In Fig. 8, the table 71 remains in the same position while the middle plunger 100 is elevated to force the cap 107 into tube 104. Table 71 is now moved by the pawl 72 and ratchet 74 into position to bring the cap 108 under the tube 104. While in this position however, the cap 109 is displaced into the tube 103. At the same time an additional cap 116 has been formed in the first unoccupied die. As shown in Fig. 10 the table is moved again to bring 108 under the tube 105 in which position the cap 111 is brought under tube 102. Said cap 111 is then elevated into the tube 102 while at the same time a new cap 117 has been formed in the next unoccupied die. After the table has been rotated into the position shown in Fig. 11 in which the cap 108 is brought under tube 106, said cap 108 is elevated into the tube 106 while at the same time a new cap 118 has been formed in the next unoccupied die. The table is now moved into the position shown in Fig. 12 in which the cap 110 has been brought under the tube 105, said cap being displaced into said tube and a new cap 119 formed in the next unoccupied die. It will be seen therefore that during these successive operations, caps are forced into the tubes in the following order, namely, 104, 103, 102, 106, 105, 104, etc. From an inspection of these diagrams it will be seen that the distribution between these tubes is uniform while at the same time no cap is allowed to pass all of the tubes without being forced into one of them. In order to hold the table against movement, during these cap displacing operations the cam 120 (see Fig. 1) is keyed to the shaft 12 and serves to engage a cam roller 121 carried by a vertical reciprocating bar 122 which engages an arm 123 for oscillating a lock bar 124 which is

yieldably forced into engagement with suitable notches in the periphery of the table 71. 65

I claim:

1. In a machine of the character described, a plurality of cap-stacking receptacles arranged in a series, cap-forming means including dies suitably mounted to successively register with said receptacles, and means for displacing caps from said dies into said receptacles. 70

2. In a machine of the character described, a plurality of cap-stacking receptacles arranged in a series, cap-forming means including dies suitably mounted to successively register with said receptacles, and means for displacing caps from the respective dies into different receptacles. 75

3. In a machine of the character described, a rotary table provided with cap-forming dies, cap-stacking receptacles, means for mounting said receptacles in position to be traversed by said dies, and means for displacing caps from said dies into said receptacles. 80

4. In a machine of the character described, a plurality of cap-stacking receptacles arranged in a series, cap-displacing means operatively arranged with respect to each of said receptacles, cap-forming means including a die movable into and out of registry with each of said receptacles, and means for separately operating each of said cap-displacing means. 90

5. In a machine of the character described, the combination with a movable table provided with cap-forming dies, of means co-operating with said dies to form caps, a plurality of cap-holders arranged to have dies on said table brought into registry therewith, and means for moving caps from said dies in predetermined order into different cap-holders. 100

6. In a machine of the character described, the combination with a movable table provided with cap-forming dies, of means co-operating with said dies to form caps, a plurality of cap-holders arranged to have dies on said table brought into registry therewith, and means for moving caps from said dies to said cap-holders, said cap-moving means being adapted to move successive caps to different cap-holders. 115

7. In a machine of the character described, a cap-forming member, a plurality of sockets for cap-holders, cap-holders separately and removably mounted in said sockets, 120 a rotary table provided with a plurality of cap-forming members adapted to co-operate successively with the first mentioned cap-forming member, said table being journaled upon an axis suitably disposed to bring the cap-forming members carried thereby into register with said cap-holders, 125 said cap-forming members on the table be-

ing adapted to carry caps, and means for dis-
placing caps from the cap-forming members
on said rotary table into said cap-holders.

8. In a machine of the character described,
5 a bracket or support provided with a plural-
ity of sockets therein, cap-holders removably
mounted in said sockets, said holders being
provided with openings through which caps
may be forced into said holders, means for
10 feeding caps into register with said open-
ings, and separately actuated means for forcing
successive caps into different holders.

9. In a machine of the character described,
15 cap-holders supporting means, cap-holders
removably mounted thereon, said supporting
means being provided with openings
through which caps may be charged into
said holders, a reciprocable plunger for forcing
caps into each of said holders, and means
20 for feeding caps into positions between said
holders and the respective plungers corre-
sponding thereto.

10. In a machine of the character de-
scribed, cap-holders supporting means, cap-
holders removably mounted thereon, said
supporting means being provided with open-
ings through which caps may be charged
into said holders, a reciprocable plunger for
forcing caps into each of said holders, and
means for feeding caps into positions be-
tween said holders and the respective plun-
gers corresponding thereto, said machine be-
ing provided with means for operating said
plungers separately in predetermined order.

11. In a machine of the character de- 35
scribed, a series of cap-holders arranged on
fixed axes, cap - forming means including
cap-shaping dies suitably mounted to move
into coaxial alinement with said cap-hold-
ers, and plungers arranged coaxially with 40
said cap-holders and adapted to move caps
from said dies into said cap-holders.

12. In a machine of the character de-
scribed, a series of cap-holders arranged on
fixed axes, cap - forming means including 45
cap-shaping dies suitably mounted to move
into coaxial alinement with said cap-hold-
ers, plungers arranged coaxially with said
cap-holders and adapted to move caps from
said dies into said cap-holders, and means 50
for actuating said plungers at different
times.

13. In a machine of the character de-
scribed, a series of cap-holders arranged on
fixed axes, cap - forming means including 55
cap-shaping dies suitably mounted to move
into respective coaxial alinement with said
cap-holders, plungers respectively arranged
coaxial with said cap-holders and adapted
to move caps from said dies into said cap-
holders, and means for actuating said plun-
gers at different times, said cap - shaping
dies being provided with means for chang-
ing their positions after the actuation of
each of said plungers. 60

ELOF NORDSTROM.
